UNITED STATES PATENT OFFICE.

MURILLO DOWNER, OF CHICAGO, ILLINOIS.

VEHICLE.

No. 820,707.

Specification of Letters Patent.

Patented May 15, 1906.

Application filed April 11, 1904. Serial No. 202,512.

To all whom it may concern:

Be it known that I, MURILLO DOWNER, a citizen of the United States, residing at Chicago, in the county of Cook and State of Illinois, have invented a certain new and useful Improvement in Vehicles, of which the following is a specification.

My invention relates to vehicles, and has for its object to provide certain new and useful improvements therein.

My invention is illustrated in the accompanying drawings, wherein—

Figure 1 is an inverted plan view of a vehicle embodying my invention. Fig. 2 is a sectional view on line 2 of Fig. 1. Fig. 3 is a detail view of the air-cushioning device shown in section. Fig. 4 is a longitudinal sectional view similar to that shown in Fig. 2, but of a modified form of my invention. Fig. 5 is a detail view of another modification in section.

Like parts are designated by like letters of reference in all of the drawings.

A A are longitudinal supporting-beams connected and forming a part of the vehicle-body, the ends of which are preferably curved downward.

A' A' are cross braces or supports.

B B B B represent the lever-arms by means of which the running-gear is connected to the supports A A of the body. I have shown these lever-arms as being connected to the supports A A; but it will be obvious that they might as well be connected immediately to the vehicle-body, if desired. There are four of these lever-arms and four sets of cushioning and supporting apparatus connected therewith, as shown in Figs. 1 and 2, one at each corner of the vehicle, but as all are alike it will be sufficient to describe one of them. Each of the lever-arms B is preferably curved upward at one end and is pivotally connected by the pin B', somewhat loosely, so as to give a free motion to the link B², which is similarly connected with an end of one of the supports A by another pin B³. The other end of the arm B is provided with a suitable socket B⁴, which receives the ball C' of the plunger-rod C. C has at its other extremity the ball C², so as to provide for another ball-and-socket joint.

D D are axles of the vehicle, and E E E E the vehicle-wheels.

Each lever-arm B is connected to its axle by collars F F, having perforated lugs F' F'. One of these lugs passes on each side of arm

B, which has a perforation registering with the perforations of the lugs F' F'. A pin F² passes through these perforations and connects collars F F and arm B, so as to allow 60 the arm B to rock on the pin F² as a pivot.

Associated with each lever B is an air-cylinder G, suitably fastened to the supports A A of the vehicle-body and of any preferred sort. The cylinder G has a plunger G' therein, which is provided with a suitable socket to receive the ball C² of rod C.

H is an air-storage tank supplying the cylinders. Tank H is supplied through pipe H', having the check-valve H² and the shut-off 70 valve H³ and the removable cap H⁴.

H⁵ is a pressure-regulating valve in the pipe H⁶, which leads from tank H to the pipes H⁷, which in turn conduct the air to the cylinders G through the check-valves H⁸, 75 there being one of these check-valves for each cylinder. Each cylinder G is also provided with a safety-valve J, located in the outlet-pipe J' and operated by the crank J² and its depending rod J³, such rod being hooked at 80 its lower end, so as to engage with the lever-arm B.

In operation when the pressure in the air-cylinder becomes excessive, so as to raise the body of the vehicle above a certain point, the 85 valve J will be automatically opened, so as to allow the escape of air from the cylinder.

Fig. 5 is a detail view showing a modified form of the invention, wherein the arm B is slightly different in shape and is pivoted to a 90 downwardly-projecting part A² on the support A. The connection with the cylinder is the same as shown in Figs. 1 and 2; but in this form the connection with the running-gear is made by a roller B⁵, which is pivoted 95 on the arm B and which rests upon the bolster L, to which the running-gear is connected. By giving to this bolster L the proper shape this form of my invention may be adapted for use in cases where it is desired to turn a 100 portion of the running-gear with respect to the wagon-body—as, for example, when the vehicle is to be steered by turning the entire front axle and wheels. This arrangement of the cushioning devices and also that shown in 105 Figs. 1 and 2, as has been said, contemplates the use of four sets of cylinders and lever-arms, one at each corner of the vehicle; but this is not necessary to the carrying out of my invention, and in Fig. 4 I have shown a modification wherein but one cylinder is used upon each side of the vehicle. In such case the le-

ver-arms B are made somewhat longer, their ends being overlapped and slotted at B³, so as to receive a transverse pin C³ upon the end of rod C. In this form of my invention the cylinders G, one on each side of the vehicle, are placed midway between the ends of the supports A A.

I have thus described in detail three forms of devices embodying my invention; but it is obvious that there might be a wide departure from the particular forms and constructions and arrangements of parts as above shown without going outside of the broad scope of my invention, and therefore I do not limit myself to the particular forms, devices, and arrangements described.

The use and operation of my device are as follows: The tank H is supplied with air or other suitable fluid through the pipe H' and delivers an equal pressure of the fluid to all of the cylinders, the amount being regulated by the pressure-diminishing valve H⁵. The cylinders G will obviously perform the function of air-cushions, acting in connection with the pivoted lever-arms to give the wagon-body a secure but elastic seat upon the running-gear. The advantages of this disposition of air-cushions and of the use of the pivoted supporting parts are several. The cylinders, for example, may be located elsewhere than in the customary place upon the axle. This is desirable particularly in the case of motor-cars, where the space about the axles is frequently required for motor mechanism. As shown in Fig. 4, two air-cylinders may be made to suffice to cushion the vehicle, if desired. The use of the levers in connection with the air-cylinders has also this decided advantage, that the cylinders may be thus located in any desired places upon the lower part of the vehicle-body and on either side of the axle. Therefore by making the lever of considerable length from its fulcrum on the running-gear to its connection with the plunger a long stroke is given to the plunger, and consequently a relatively great spring to the vehicle on an amount of pressure smaller than would otherwise be possible. As my form of supporting and cushioning device engages with the vehicle-body at numerous places—for example, in the first two forms shown at eight different points and in the last at six—it will be clear that the strain on the vehicle is better distributed than customarily, thus saving wear and tear thereon.

I claim—

1. A vehicle comprising a vehicle-body and running-gear in combination with an air-cushion device on the vehicle-body and a supporting-lever, such supporting device being interposed between the vehicle-body, its running-gear and such cushioning device.

2. A vehicle comprising a body and running-gear in combination with a fluid-pres-

sure cushion on the vehicle-body, and a supporting device connected at different points longitudinally thereon with the fluid-pressure cushion, the body of the vehicle and its running-gear.

3. A vehicle comprising a vehicle-body, running-gear, a fluid cushioning device, and a lever fulcrumed on the running-gear and being engaged at opposed points thereupon by the vehicle-body and such fluid cushioning device.

4. In a vehicle the combination of a vehicle-body, running-gear, a fluid-pressure device on the vehicle-body, and a supporting-lever interposed between the vehicle-body and its running-gear and associated with the fluid-pressure device so as to put the same in operation under the load of the vehicle.

5. In a supporting and cushioning device for vehicles the combination of an air-cylinder connected with the vehicle-body, a plunger in such cylinder, and a supporting device associated with the running-gear and movably connected at different points on such device with the wagon-body and with the plunger of such cylinder so as to transmit the pressure of the vehicle-body against the air in the cylinder.

6. In a supporting and cushioning device for vehicles the combination of a cylinder with a plunger therein, and a supporting device connected with the running-gear of the vehicle and associated at points on either side of the place of its connection with the running-gear, respectively with the vehicle-body and the cylinder-plunger, so as to support such vehicle-body against the pressure of fluid in the cylinder.

7. In a supporting and cushioning device for vehicles the combination of an air-cylinder connected with the vehicle-body, a plunger in such cylinder, a supporting device associated with the running-gear and connected with the vehicle-body and with the plunger of such cylinder, so as to cushion the vehicle-body against the air in the cylinder, a safety-valve associated with such cylinder, and means connected with the supporting device for automatically operating such valve under predetermined conditions.

8. In a supporting and cushioning device for vehicles the combination of an air-cylinder connected with the vehicle-body, a plunger in such cylinder, and a supporting device associated with the running-gear and movably connected with the wagon-body and with the plunger of such cylinder so as to cushion the vehicle-body against the air in the cylinder, such supporting device comprising a lever fulcrumed upon a part of the running-gear and having pivoted links at each end thereof for making connections with the wagon-body and with the plunger.

9. A vehicle comprising a vehicle-body and running-gear in connection with a plurality

of air-cushions, a plurality of supporting devices movably connected with the vehicle-body and with the air-cushions, and fulcrumed on a part of the running-gear of the vehicle, and an air-storage tank with connections to the several air-cushions.

10. A vehicle comprising a vehicle-body, longitudinal supporting-beams connected therewith, a plurality of fluid-pressure cylinders having plungers therein a plurality of supporting devices movably connected near their respective extremities with the supporting-beams and with the plungers of such fluid-pressure cylinders, and bearing upon 15 the running-gear of the vehicle so as to transmit the load of the vehicle against the fluid in such cylinders, and a fluid-storage device with suitable connections and valves to deliver an equal pressure to all of such fluid-pressure cylinders.

11. A supporting and cushioning device for vehicles comprising an air-cushion, a hanger device on the axle of the vehicle, and a supporting-beam pivotally attached to the 25 vehicle-body near one end, associated with

the air-cushion near the other end, and pivotally connected with the hanger device therebetween.

12. A supporting and cushioning device for vehicles comprising an air-cushion, a supporting-beam pivotally attached to one end to the body of the wagon, and associated at the other end with the air-cushion, and a movable device on such supporting device adapted to give a movable connection between such supporting-beam and the running-gear of the vehicle.

13. In a cushioning device for vehicles, the combination of an air-cushion comprising a cylinder and a piston with a lever, the lever being connected with the supporting and supported parts of the vehicle with the piston of such air-cushion so as to transmit the pressure of the load against the air-cushion device.
